UNITED STATES PATENT OFFICE.

PRESTON H. ALLEN AND HENRY H. ALLEN, OF ST. LOUIS, MISSOURI, ASSIGNORS TO
BEMIS BRO. BAG COMPANY, OF ST. LOUIS, MISSOURI, A CORPORATION OF MISSOURI.

FASTENER FOR CONTAINERS OR ENVELOPS.

1,314,781.

Specification of Letters Patent.

Patented Sept. 2, 1919.

Application filed May 7, 1918. Serial No. 233,127.

To all whom it may concern:

Be it known that we, PRESTON H. ALLEN and HENRY H. ALLEN, citizens of the United States, and residents of St. Louis, Missouri, have invented certain new and useful Improvements in Fasteners for Containers or Envelops, of which the following is a specification containing a full, clear, and exact description, references being had to the accompanying drawings, forming a part hereof.

Our invention relates to certain new and useful improvements in "fasteners for containers or envelops" and has for its special object the construction of a fastening member which is attached to the container body, which should be imperforate to prevent the entrance of moisture or dirt into the body of the container.

20 In the drawings,

Figure 1 is a perspective view of a waterproof container with our invention applied thereto, illustrating the fastener holding the container closed.

25 Fig. 2 is a central longitudinal section taken through the container or envelop, and both fastening members.

Fig. 3 is an enlarged sectional view taken through the fastener which is secured to the body of the container, with parts of the container broken away.

30 Fig. 4 is a similar view wherein we employ a different construction of metallic plug or rivet for making the fastener imperforate.

35 Fig. 5 is a sectional elevation of a split rivet which we employ, and

Fig. 6 is a sectional elevation of a modified form of rivet, which we may employ in carrying out our invention.

40 Referring to the drawings, 7 indicates the body of the container which is composed of waterproof material, the sides being closed by means of stitching 8. The mouth of the container is closed by means of a folded flap 9, comprising two folds 10 and 11, carrying a flap 12 which when the container is closed occupies the position over and against the top edge 13 of the mouth of the container, as illustrated in Figs. 1 and 2.

45 The container itself is made the subject of a separate application executed by us on even date herewith, and no further description of the container *per se* is deemed necessary in this application which is directed to the fastening device.

Secured to the folded flap 9 of the container is a fastener which comprises a metal tubular rivet 14 provided with a flange 15 and two disks 16 and 17, the disk 16 being of heavier material than the disk 17.

These disks 16 and 17 are perforated and the tubular metal rivet 14 passes through the disks and also through the folds 10 and 11 of the folded flap 9; and the end of the tubular rivet 14 is upset or flanged as at 18 by means of a punch or any suitable mechanical device, thus securely uniting the two disks of the fastener and the fastener itself to the folded flap 9.

It is not necessary to have the fastener 70 which is secured to the folded flap imperforate because it is not in communication with the interior of the container.

In conjunction with the fastener just described which is secured to the folded flap 75 we employ an imperforate fastener 19 secured to the body of the container 7. This fastening member 19 is likewise composed of a tubular rivet 14 having a flange 15 and an upset or flanged lower end 20 and 80 two disks 16 and 17 which are secured to the body of the container in the same manner as the fastener previously described is secured to the folded flap 9 of the container.

Located in the tubular rivet or sleeve 14 85 is a rivet 21 provided with a head 22 overlying the flange 15 of the tubular rivet 14. The rivet 21 may be of the split type as illustrated in Figs. 2, 3 and 5, or of the hollow tubular type as illustrated in Figs. 4 and 90 6. The shank of the rivet 21 is of sufficient size so as to snugly fit the tubular sleeve or rivet 14, so as to make a tight waterproof and dust proof joint, and is of sufficient length so that its lower end may be 95 upset or flanged over the flanged end 20 of the tubular rivet 14, as illustrated in Figs. 2 and 3 wherein the lower end of the rivet 21 is flanged over the flange 20 of the hollow rivet 14 by means of a flange 23.

100 The upsetting of the end of the rivet 21 and forming the flange thereon, not only forms a waterproof imperforate joint, but it also has a tendency to more firmly clamp and bind the disks 16 and 17 against the 105 body of the container. In other words, the employment of the rivet 21 and upsetting or flanging its end reinforces and strengthens the connection between the fastener disks and material located between them. 110

The upsetting of the end of the rivet 21 and forming a flange thereon contacting with the flange 20 tightens the same against the material located between the disks.

5 Carried by the fastener located on the folded flap 9 is a flexible cord 24, one end of which is secured to the fastener carried by the folded flap, and the opposite end is wrapped around the fastener as illustrated 10 in Fig. 1, the fastening cord 24 being wrapped between the disk 16 and the body of the container.

The fastening cord 24 connects or fastens together the fastening member carried by 15 the folded flap 9, and the fastening member 19 carried by the body of the container.

The fastening member secured to the folded flap 9 of the container, and the fastening member secured to the body of the 20 container are constructed alike with the exception of the rivet 21, which renders the fastening member 19 imperforate and also more securely fastening it to the body of the container as previously described.

25 Having fully described our invention, what we claim is:

A fastener for waterproof containers or envelopes comprising two members capable

Copies of this patent may be obtained for five cents each, by addressing the "Commissioner of Patents, Washington, D. C."

of being attached to the parts to be fastened, each member being composed of a 30 pair of disks between which the parts to be fastened together are positioned, a tubular rivet passing through each pair of disks and the material between the same, said tubular rivet being provided with a peripheral flange 35 resting against one of the disks and with an upset flanged end resting against the other disk, a rivet provided with an imperforated head located in the tubular rivet of one of the fastening members and having 40 its opposite end upset so as to completely close and render imperforate the said fastening member, and a flexible cord having one end secured to one of the fastening members and its other end adapted to be 45 wrapped around the other fastening member and below the outer disk of said member.

In testimony whereof, we have signed our names to this specification, in presence of 50 two subscribing witnesses.

PRESTON H. ALLEN.
